(57) **ABSTRACT**

An image forming apparatus includes: a heater; an endless belt; a rotary body configured to form a nipping region in cooperation with the heater; a nipping pressure changing mechanism configured to change a nipping pressure at the nipping region between a first nipping pressure and a second nipping pressure higher than the first nipping pressure; and a controller configured to perform a control process including: determining whether the nipping pressure is the first nipping pressure or the second nipping pressure; and controlling, when determining that the nipping pressure is the first nipping pressure, an output of the heater within a range that does not exceed an upper limit for the output of the heater when the nipping pressure is the first nipping pressure that is smaller than an upper limit for the output of the heater when the nipping pressure is the second nipping pressure.

**IMAGE FORMING APPARATUS
CONFIGURED TO CONTROL OUTPUT OF
HEATER DEPENDING ON NIPPING
PRESSURE AT NIPPING REGION**

REFERENCE TO RELATED APPLICATIONS

This application claims priority from Japanese Patent Application No. 2022-104693 filed on Jun. 29, 2022. The entire content of the priority application is incorporated herein by reference.

BACKGROUND ART

There has been conventionally known an image forming apparatus including a heater, a belt, a pressure roller configured to nip the belt in cooperation with the heater to form a nipping region, and a pressure detection switch for detecting that a pressure is applied to the belt and the pressure roller. In such an image forming apparatus, when a pressure is applied to the belt and the pressure roller, the pressure detection switch is turned ON to enable power supply to the heater. On the other hand, when the pressure is not applied to the belt and the pressure roller, the pressure detection switch is turned OFF to cause power supply to the heater to be interrupted.

DESCRIPTION

Since power supply to the heater is interrupted when a nipping pressure at the nipping region is low in the above configuration, an image cannot be fixed to a sheet in a state where the nipping pressure is low. In a case where the conventional image forming apparatus is configured such that power supply is performed even in a state where the nipping pressure is low, there is a possibility that heat is not properly transferred from the heater to the belt and the pressure roller, which may result in heat accumulation in the heater to cause excessive temperature rise of the heater.

In view of the foregoing, it is an object of the present disclosure to provide an image forming apparatus that can suppress excessive rise in the temperature of a heater caused by power supply to the heater when a nipping pressure is low.

In order to attain the above and other object, the present disclosure provides an image forming apparatus including: a heater; an endless belt; a rotary body; a nipping pressure changing mechanism; and a controller. The heater includes: a substrate; and one or more heating elements. The endless belt is circularly movable around the heater. The rotary body is configured to nip, in cooperation with the heater, the belt therebetween to form a nipping region. The nipping pressure changing mechanism is configured to change a nipping pressure at the nipping region between: a first nipping pressure; and a second nipping pressure that is higher than the first nipping pressure. The controller is configured to perform a control process to control output of the heater. The control process includes: determining whether the nipping pressure is the first nipping pressure or the second nipping pressure; and controlling, when determining that the nipping pressure is the first nipping pressure, the output of the heater within a range that does not exceed a first output upper limit that is an upper limit for the output of the heater when the nipping pressure is the first nipping pressure. The first output upper limit is smaller than a second output upper limit that is an upper limit for the output of the heater when the nipping pressure is the second nipping pressure.

In the above configuration, when the nipping pressure is low, the output of the heater is restricted to a value that does not exceed the first output upper limit. Accordingly, excessive rise in the temperature of the heater caused by power supply to the heater when the nipping pressure is low can be suppressed.

According to another aspect, the present disclosure also provides an image forming apparatus including: a heater; an endless belt; a rotary body; and a controller. The heater includes: a substrate; and a plurality of heating elements. The heating elements are provided on the substrate and are arranged in a conveying direction of a sheet. The heating elements includes: a first heating element; and a second heating element. The first heating element is positioned most upstream among the heating elements in the conveying direction. The first heating element has a most upstream end in the conveying direction. The second heating element is positioned most downstream among the heating elements in the conveying direction. The second heating element has a most downstream end in the conveying direction. The endless belt is circularly movable around the heater. The rotary body is configured to nip, in cooperation with the heater, the belt therebetween to form a nipping region. The nipping region has a length in the conveying direction that can be changed between: a first length that is shorter than a distance in the conveying direction between the most upstream end and the most downstream end; and a second length that is longer than the distance in the conveying direction between the most upstream end and the most downstream end. The controller is configured to perform a control process to control output of the heater. The control process includes: controlling, when the length in the conveying direction of the nipping region is the first length, the output of the heater within a range that does not exceed a first output upper limit that is an upper limit for the output of the heater when the length in the conveying direction of the nipping region is the first length. The first output upper limit is smaller than a second output upper limit that is an upper limit for the output of the heater when the length in the conveying direction of the nipping region is the second length.

In the above configuration, the controller restricts the output of the heater to a value that does not exceed the first output upper limit when the length in the conveying direction of the nipping region is short. This operation can suppress excessive rise in the temperature of the heater caused by power supply to the heater when the length in the conveying direction of the nipping region is short.

FIG. 1 is a schematic view illustrating a configuration of a laser printer.

FIG. 2A is a cross-sectional view of a fixing device.

FIG. 2B is a partially enlarged cross-sectional view of a portion in the vicinity of a heater.

FIG. 3A is a schematic view illustrating a surface of the heater at which heating resistors are provided.

FIG. 3B is a schematic view illustrating another surface of the heater at which a heat conductive member is provided.

FIG. 3C is a cross-sectional view of the heater and components in the vicinity thereof taken along a plane extending in a longitudinal direction of the heater.

FIG. 4A is a cross-sectional view of a nipping pressure changing mechanism in a state where a nipping pressure is a first nipping pressure.

FIG. 4B is a partially enlarged cross-sectional view of the portion in the vicinity of the heater in a state where the nipping pressure is the first nipping pressure.

FIG. 5A is a cross-sectional view of the nipping pressure changing mechanism in a state where the nipping pressure is a second nipping pressure.

FIG. 5B is a partially enlarged cross-sectional view of the portion in the vicinity of the heater in a state where the nipping pressure is the second nipping pressure.

FIG. 6 is a flowchart illustrating steps executed by a controller.

FIG. 7A is a view illustrating a first table.

FIG. 7B is a view illustrating a second table.

FIG. 8 is a flowchart illustrating steps executed by a controller.

FIG. 9A is a view illustrating a third table.

FIG. 9B is a view illustrating a fourth table.

EMBODIMENT

Hereinafter, one embodiment of the present disclosure will be described while referring to the accompanying drawings.

As illustrated in FIG. 1, a laser printer 100 as an example of the image forming apparatus includes a main casing 120, a feeding unit 130, an exposure unit 140, a process cartridge 150, a fixing device 1, a controller 500, and a memory 600.

The main casing 120 has a first opening H1 and a second opening H2 (an example of the opening), and includes a front cover 121 configured to open and close the first opening H1, a manual feed tray 122, a rear cover 123 (an example of the cover) configured to open and close the second opening H2, and a discharge tray 124. The first opening H1 is an opening allowing the process cartridge 150 to pass therethrough. The manual feed tray 122 is a tray used when a sheet S (for example, a thick sheet such as a post card) is conveyed along a linear conveying path and printing is performed thereon. In the following description, printing performed along the linear conveying path will also be referred to as "straight printing".

The second opening H2 is an opening through which the sheet S discharged from the fixing device 1 passes during the straight printing. The rear cover 123 is opened when the straight printing is performed to support the sheet S discharged through the second opening H2. The discharge tray 124 is a tray for supporting the sheet S discharged out of the main casing 120 in a state where the rear cover 123 is closed.

The laser printer 100 further includes a cover sensor SE1 (an example of the sensor) configured to detect whether the rear cover 123 closes the second opening H2. Information detected by the cover sensor SE1 is outputted to the controller 500.

The feeding unit 130 is a mechanism for feeding the sheet S toward a photosensitive drum 151 (described later). The feeding unit 130 includes a sheet tray 131, a lifter plate 132, and a feeding mechanism 133. The sheet tray 131 is configured to accommodate the sheet(s) therein. The sheets S accommodated in the sheet tray 131 are lifted upward by the lifter plate 132, and are separated one by one by the feeding mechanism 133 to be fed toward the process cartridge 150.

The exposure unit 140 includes a laser light source, a polygon mirror, lenses, and a reflecting mirror those are not illustrated. The exposure unit 140 is configured to emit a laser beam on the basis of image data from the laser light source to expose a circumferential surface of the photosensitive drum 151 to light.

The process cartridge 150 is attachable to and detachable from the main casing 120 through the first opening H1. The

process cartridge 150 includes the photosensitive drum 151, a charger 152, a developing roller 153, and a transfer roller 154.

The charger 152 is configured to charge the circumferential surface of the photosensitive drum 151. The exposure unit 140 is configured to expose the circumferential surface of the photosensitive drum 151 charged by the charger 152 to form an electrostatic latent image on the circumferential surface of the photosensitive drum 151.

10 The developing roller 153 is configured to supply toner in the process cartridge 150 to the electrostatic latent image formed on the circumferential surface of the photosensitive drum 151. Through this process, a toner image is formed on the circumferential surface of the photosensitive drum 151.

15 Thereafter, a sheet S fed from the feeding unit 130 passes between the photosensitive drum 151 and the transfer roller 154, whereby the toner image on the circumferential surface of the photosensitive drum 151 is transferred onto the sheet S.

20 The fixing device 1 is configured to fix the toner image to the sheet S. The sheet S having the toner image fixed thereto is discharged onto the discharge tray 124 by a pair of discharge rollers 125.

25 As illustrated in FIG. 2A, the fixing device 1 includes a heating unit 2, a pressure roller 3 as an example of the rotary body, and a frame 4.

30 The pressure roller 3 is a rotatable roller. The pressure roller 3 includes a solid cylindrical shaft 3A, and a hollow cylindrical roller portion 3B. The shaft 3A is made of metal, for example. The roller portion 3B is made of rubber, for example. The roller portion 3B covers a part of the shaft 3A.

35 As illustrated in FIGS. 2A and 2B, the heating unit 2 includes a heater 10, a holder 20, a heat conductive member 30, a stay ST, a belt BL, and a temperature sensor SE2. The heater 10 is configured to heat the belt BL to heat the sheet S through the belt BL. The temperature sensor SE2 is configured to detect a temperature of the heater 10 and to output the detected temperature to the controller 500. The temperature sensor SE2 is in contact with the heat conductive member 30.

40 As illustrated in FIG. 2B, the pressure roller 3 is configured to nip, in cooperation with the heater 10, the belt BL therebetween to form a nipping region NP. The heater 10 includes a substrate 11, heating resistors 12 (an example of the heating element) provided on the substrate 11, and a cover 13. The substrate 11 is an elongated rectangular plate made of ceramic material such as aluminum oxide. The heater 10 is a so-called ceramic heater.

45 Each of the heating resistors 12 is formed on one surface of the substrate 11 by printing. As illustrated in FIG. 3A, two of the heating resistors 12 are provided in the present embodiment. However, three or more of the heating resistors 12 may be provided. The two heating resistors 12 extend parallel to each other in a longitudinal direction of the heater 55 10 and arranged to be spaced apart from each other in a short direction orthogonal to the longitudinal direction. In other words, the two heating resistors 12 are provided on the substrate 11 such that the heating resistors 12 are arranged in a conveying direction of the sheet S. In the following description, the conveying direction of the sheet S at the nipping region NP will also be simply referred to as "conveying direction".

55 Each of the heating resistors 12 has one end 12A connected to one end of a lead wire 19A. Each of the lead wires 19A has another end provided with a power feed terminal 18 configured to supply power to the corresponding heating resistor 12.

Each of the power feed terminals **18** is electrically connected to the corresponding heating resistor **12** through the corresponding lead wire **19A**. The power feed terminals **18** are provided at one end portion **11E** in the longitudinal direction of the substrate **11**. As illustrated in FIG. 3C, a connector C configured to supply power to the heater **10** is connected to the power feed terminals **18**. The connector C is attachable to and detachable from to one end portion in the longitudinal direction of the heater **10**. The power feed terminals **18** are configured to receive power from the connector C when the connector C is attached to the heater **10**. In FIG. 3C, the heating resistors **12**, the cover **13**, and the belt **BL** are not illustrated to facilitate understanding.

Each of the heating resistors **12** also has another end **12B** opposite the one end **12A**. The other ends **12B** of the heating resistors **12** are connected to each other through a lead wire **19B**. Note that the number of heating resistors **12** is not particularly limited. Further, the heating resistors **12** may be configured of two types of heating resistors: a first heating resistor and a second heating resistor elongated in the longitudinal direction. The first heating resistor may have a longitudinal center portion configured to generate a heat quantity greater than that generated at longitudinal end portions thereof, and the second heating resistor may have longitudinal end portions configured to generate a heat quantity greater than that generated at a longitudinal center portion thereof. The first and second heating resistors may be controlled individually in order to control distribution of heat generation with respect to the longitudinal direction.

As illustrated in FIG. 2B, the cover **13** covers the heating resistors **12**. The cover **13** is made of glass, for example.

As illustrated in FIG. 2A, the holder **20** supports the heater **10**, and is configured to guide the belt **BL**. The holder **20** is made of resin, for example.

The stay **ST** supports the holder **20**. The stay **ST** is made of metal, for example.

The belt **BL** is an endless belt, and is made of metal or resin. The belt **BL** is circularly movable around the heater **10** while the belt **BL** is guided by the holder **20**. The belt **BL** has an outer peripheral surface, and an inner peripheral surface. The outer peripheral surface contacts the pressure roller **3** or the sheet **S** as a target to be heated. The inner peripheral surface contacts the heater **10**.

The heat conductive member **30** is configured to conduct heat in the longitudinal direction of the heater **10** so as to provide uniform temperature along the entire length of the heater **10** in the longitudinal direction. The heat conductive member **30** has a plate-like shape and is positioned between the heater **10** and the holder **20**. The heat conductive member **30** contacts another surface of the substrate **11** which is opposite the one surface. When a sheet **S** is nipped between the heating unit **2** and the pressure roller **3** at the nipping region **NP**, the heat conductive member **30** is nipped between the heater **10** and the holder **20**. The heat conductive member **30** is made of aluminum, for example.

As illustrated in FIGS. 3A and 3B, with respect to the longitudinal direction, the one end **12A** and the other end **12B** of each heating resistor **12** are positioned outward of a maximum width **W** of the sheet **S** applicable to the heating unit **2**, and positioned inward of one end **30A** and another end **30B** of the heat conductive member **30**, respectively. That is, the heat conductive member **30** has a length in the longitudinal direction greater than that of the heating resistors **12**.

The substrate **11** has a length in the longitudinal direction greater than that of the heat conductive member **30**. The one end **30A** of the heat conductive member **30** is positioned

inward of one end **11A** of the substrate **11** in the longitudinal direction. The other end **30B** of the heat conductive member **30** is positioned inward of another end **11B** of the substrate **11** in the longitudinal direction.

As illustrated in FIG. 4A, the fixing device **1** further includes a nipping pressure changing mechanism **NM**. The nipping pressure changing mechanism **NM** is configured to change a nipping pressure at the nipping region **NP** between a first nipping pressure (an example of the second nipping pressure) and a second nipping pressure (an example of the first nipping pressure) that is lower than the first nipping pressure. The nipping pressure changing mechanism **NM** includes a shaft **SF**, a pair of pressure arms **60**, a pair of pressure springs **70**, and a pair of cams **80**. The frame **4** supports the pressure springs **70**, and supports the pressure arms **60** and the cams **80** so that the pressure arms **60** and the cams **80** are pivotally movable.

One of the pressure arms **60**, one of the pressure springs **70**, and one of the cams **80** are provided at each end portion of the frame **4** in an axial direction of the pressure roller **3**. In the following description, the axial direction of the pressure roller **3** will also be simply referred to as "axial direction". The pressure arm **60**, the pressure spring **70**, and the cam **80** positioned at one end portion of the frame **4** in the axial direction are identical to those positioned at another end portion of the frame **4** in the axial direction in the present embodiment. Hence, for simplifying description, only the pressure arm **60**, the pressure spring **70**, and the cam **80** positioned at the one end portion of the frame **4** in the axial direction will be described.

The shaft **SF** extends in the axial direction. The shaft **SF** is made of metal, for example. The shaft **SF** is pivotally movably supported by the frame **4**. The shaft **SF** has each end portion in the axial direction to which the cam **80** is fixed. The cam **80** is pivotally movable in accordance with pivotal movement of the shaft **SF**.

The pressure arm **60** is configured to press the heating unit **2** toward the pressure roller **3**. The pressure arm **60** is pivotally movably supported by the frame **4**.

The pressure spring **70** is a tension coil configured to urge the pressure arm **60** toward the pressure roller **3**. The pressure spring **70** has one end connected to the pressure arm **60**, and another end connected to the frame **4**.

The cam **80** is configured to press the pressure arm **60** against an urging force of the pressure spring **70**. Specifically, the cam **80** is pivotally movable between a first position (a position illustrated in FIG. 4A) and a second position (a position illustrated in FIG. 5A). The cam **80** is pivotally movable as a driving force is supplied from a motor (not illustrated) in the laser printer **100** through the shaft **SF**.

The nipping pressure at the nipping region **NP** is the first nipping pressure when the cam **80** is in the first position, whereas the nipping pressure at the nipping region **NP** is the second nipping pressure lower than the first nipping pressure when the cam **80** is in the second position.

FIGS. 4B and 5B illustrate dimensional relationship among the components of the fixing device **1**. The nipping region **NP** has a nipping width **Ln** which is a length in the conveying direction. The nipping width **Ln** varies depending on whether the nipping pressure at the nipping region **NP** is the first nipping pressure or the second nipping pressure. Also, the heating resistors **12** provide a distance **Lr** in the conveying direction between a most upstream end **E1** and a most downstream end **E2**. The most upstream end **E1** is a most upstream end in the conveying direction of the heating resistor **12** (an example of the first heating element) which

is positioned most upstream among the heating resistors **12** in the conveying direction. The most downstream end **E2** is a most downstream end in the conveying direction of another heating resistor **12** (an example of the second heating element) which is positioned most downstream among the heating resistors **12** in the conveying direction.

As illustrated in FIG. 4B, the nipping width L_n is longer than the distance L_r when the nipping pressure at the nipping region **NP** is the first nipping pressure. That is, the two heating resistors **12** are positioned within a range of the nipping region **NP** in the conveying direction.

As illustrated in FIG. 5B, the nipping width L_n is shorter than the distance L_r when the nipping pressure at the nipping region **NP** is the second nipping pressure. The nipping region **NP** is positioned within a range defined between the most upstream end **E1** and the most downstream end **E2** in the conveying direction.

As illustrated in FIGS. 4A and 5A, the heating unit **2** further includes a side guide **SG** provided at each end portion in the axial direction of the heating unit **2**. Each of the side guides **SG** supports a corresponding end portion of the stay **ST** in the axial direction. Each of the side guides **SG** is movably supported by the frame **4**. Each of the pressure arms **60** is configured to press the corresponding side guide **SG** toward the pressure roller **3**.

The controller **500** includes a CPU, a ROM, a RAM, a non-volatile memory and the like, and is configured to perform various control operations in the laser printer **100** on the basis of a program prepared in advance. The controller **500** is configured to determine whether the rear cover **123** closes the second opening **H2** or not on the basis of the information received from the cover sensor **SE1**.

When determining that the rear cover **123** closes the second opening **H2**, the controller **500** controls the motor (not illustrated) for pivotally moving the cam **80** to cause the nipping pressure changing mechanism **NM** to make the nipping pressure at the nipping region **NP** to the first nipping pressure. On the other hand, when determining that the rear cover **123** does not close the second opening **H2**, the controller **500** causes the nipping pressure changing mechanism **NM** to make the nipping pressure at the nipping region **NP** to the second nipping pressure.

Further, the controller **500** is configured to determine whether the nipping pressure at the nipping region **NP** is the first nipping pressure or the second nipping pressure when receiving a printing instruction. Specifically, in response to receiving a printing instruction, the controller **500** determines whether or not the rear cover **123** is closed on the basis of information received from the cover sensor **SE1**. The controller **500** determines that the nipping pressure is the first nipping pressure when determining that the rear cover **123** is closed. On the other hand, the controller **500** determines that the nipping pressure is the second nipping pressure when determining that the rear cover **123** is not closed. In the present embodiment, the cover sensor **SE1** serves as a sensor configured to detect information for the controller **500** to determine whether the nipping pressure is the first nipping pressure or the second nipping pressure.

The controller **500** is configured to control the output of the heater **10** on the basis of a deviation ΔT between a target temperature T_t and a detection temperature T of the heater **10** detected by the temperature sensor **SE2**. The deviation ΔT is calculated by subtracting the detection temperature T from the target temperature T_t , for example. The controller **500** is configured to set the output of the heater **10** to a greater value as the deviation ΔT is greater.

The controller **500** is configured to control a duty cycle of power supply to the heater **10** to thereby control the output of the heater **10**. When determining that the nipping pressure is the first nipping pressure, the controller **500** determines the duty cycle on the basis of a first table (an example of the second table) illustrated in FIG. 7A and the deviation ΔT . A first duty upper limit (an example of the second duty upper limit) that is the upper limit for the duty cycle in the first table, is 100%.

When determining that the nipping pressure is the second nipping pressure, the controller **500** determines the duty cycle on the basis of a second table (an example of the first table) illustrated in FIG. 7B and the deviation ΔT . A second duty upper limit (an example of the first duty upper limit) that is the upper limit for the duty cycle in the second table, is 57%. Each of the first table in FIG. 7A and the second table in FIG. 7B is a table correlating the deviation ΔT with the duty cycle. In the present embodiment, both the first table and the second table are stored in the memory **600**.

That is, when determining that the nipping pressure is the second nipping pressure, the controller **500** controls the duty cycle within a range that does not exceed the second duty upper limit (57%) that is smaller than the first duty upper limit (100%). Thus, when determining that the nipping pressure is the second nipping pressure, the controller **500** controls the output of the heater **10** within a range that does not exceed a second output upper limit (an example of the first output upper limit) that is the upper limit for the output of the heater **10** when the nipping pressure is the second nipping pressure. The second output upper limit is smaller than a first output upper limit (an example of the second output upper limit) that is the upper limit for the output of the heater **10** when the nipping pressure is determined to be the first nipping pressure.

Next, operations performed by the controller **500** will be described in detail.

As illustrated in the flowchart of FIG. 6, in S1 the controller **500** determines whether or not a printing instruction exists. When determining in S1 that a printing instruction does not exist (S1: NO), the controller **500** ends this routine.

When determining in S1 that a printing instruction exists (S1: YES), in S2 the controller **500** determines, on the basis of information received from the cover sensor **SE1**, whether or not the nipping pressure is the first nipping pressure. The process in S2 is an example of the determining. When determining in S2 that the nipping pressure is the first nipping pressure (S2: YES), in S3 the controller **500** selects the first table illustrated in FIG. 7A. The process in S3 is an example of the selecting the second table.

When determining in S2 that the nipping pressure is not the first nipping pressure, i.e., when determining that the nipping pressure is the second nipping pressure (S2: NO), in S4 the controller **500** selects the second table illustrated in FIG. 7B. After performing the process in S3 or S4, in S5 the controller **500** acquires the temperature of the heater **10** from the temperature sensor **SE2**. The process in S4 is an example of the selecting the first table.

After the process of S5, in S6 the controller **500** calculates the deviation ΔT between the target temperature T_t and the detection temperature T detected by the temperature sensor **SE2**. Subsequently, in S7 the controller **500** sets the duty cycle on the basis of the first or second table selected in the process of S3 or S4 and the calculated deviation ΔT , and controls power supply to the heater **10** using the set duty cycle.

After the process of S7, in S8 the controller **500** determines whether or not a printing operation based on the printing instruction has been completed. When determining in S8 that the printing operation has not yet been completed (S8: NO), the controller **500** returns to the process of S5. The processes performed from the determination of S2: NO to S8 is an example of the controlling.

When determining in S8 that the printing operation has been completed (S8: YES), in S9 the controller **500** stops power supply to the heater **10**, and ends the process of FIG.

6. The processes in S1 to S9 are an example of the control process.

A specific example of the operations performed by the controller **500** will next be described.

When a user opens the rear cover **123** illustrated in FIG. 1 to perform a straight printing, the controller **500** controls the nipping pressure changing mechanism NM illustrated in FIG. 4A on the basis of information received from the cover sensor **SE1** to change the nipping pressure from the first nipping pressure to the second nipping pressure.

When receiving a printing instruction while the nipping pressure is the second nipping pressure, the controller **500** performs processes in the order of S1: YES→S2: NO→S4 to S7. As a result, the output of the heater **10** is limited to a value equal to or less than the second output upper limit (57%).

As illustrated in FIG. 5B, since the nipping width L_n when the nipping pressure is the second nipping pressure is small, the quantity of heat transmitted from the heater **10** to the pressure roller **3** through the belt **BL** decreases and heat is likely to accumulate in the heater **10**. In particular, in a configuration according to the present embodiment in which a part of each heating resistor **12** is positioned outward of the range of the nipping region **NP**, heat is more likely to accumulate in the heater **10**. However, as described above, when the nipping pressure is the second nipping pressure, the output of the heater **10** is restricted to be equal to or less than the second output upper limit, thereby restraining heat from accumulating in the heater **10**.

According to the present embodiment, the following advantages can be obtained.

When the nipping pressure is low, the output of the heater **10** is restricted to be equal to or less than the second output upper limit. Accordingly, excessive rise in the temperature of the heater **10** which is caused by supplying power to the heater **10** when the nipping pressure is low can be restrained.

When the nipping pressure is low, power supply with a large duty cycle is not performed, thereby restricting the output of the heater **10** to be equal to or less than the second output upper limit when the nipping pressure is low.

<Modifications>

While the invention has been described in conjunction with various example structures outlined above and illustrated in the figures, various alternatives, modifications, variations, improvements, and/or substantial equivalents, whether known or that may be presently unforeseen, may become apparent to those having at least ordinary skill in the art. Accordingly, the example embodiments of the disclosure, as set forth above, are intended to be illustrative of the invention, and not limiting the invention. Various changes may be made without departing from the spirit and scope of the disclosure. Therefore, the disclosure is intended to embrace all known or later developed alternatives, modifications, variations, improvements, and/or substantial equivalents. Some specific examples of potential alternatives, modifications, or variations in the described invention are provided below:

Although the duty cycle is set on the basis of the deviation ΔT in the above embodiment, the present disclosure need not be limited to this method. In this modification, the duty cycle is set on the basis of a manipulated variable U using the sum of a proportional term proportional to the deviation ΔT and a derivative term proportional to a derivative value of the deviation ΔT . Specifically, the controller **500** calculates the manipulated variable U according to the following expression (1).

$$U_n = K_p \Delta T_n + K_d D_n$$

$$D_n = (T_n - T_{n-1})/ts$$

(1)

in which ts is control cycle (time).

In the above expression, K_p is a proportional gain as a preset fixed value; K_d is a derivative gain, which is selected from either $K1$ or $K2$ depending on the nipping pressure as will be described later; D is a derivative value of the deviation ΔT ; and n added to each variable indicates that the variable is a current value, while $n-1$ indicates that the variable is a previous value.

Further, in the above expression, $K_p \Delta T_n$ is a proportional term, and $K_d D_n$ is a derivative term. The positive and negative of the proportional term and the derivative term is set so as to cancel each other in the process of the detection temperature T rising toward the target temperature Tt . In the following example, it is assumed that K_p is positive, K_d is negative, and ΔT_n and D_n become positive in the process of the detection temperature T rising toward the target temperature Tt .

The positive and negative between K_p and K_d may be reversed. That is, K_p may be negative, and K_d may be positive. Further, when ΔT_n and D_n are set to become negative in the process of the detection temperature T rising toward the target temperature Tt (for example, in a case in which $\Delta T = T_{n-1} - T_n$), the positive and negative between K_p and K_d may be reversed.

The controller **500** is configured to set the duty cycle of power supply to the heater **10** to a greater value as the absolute value of the calculated manipulated variable U is greater. When the nipping pressure is the second nipping pressure, the controller **500** sets the coefficient K_d of the derivative term to such a value that the absolute value of the calculated manipulated variable U is smaller than when the nipping pressure is the first nipping pressure.

Specifically, when determining that the nipping pressure is the first nipping pressure, the controller **500** sets the coefficient K_d to $-K1$. On the other hand, when determining that the nipping pressure is the second nipping pressure, the controller **500** sets the coefficient K_d to $-K2$. The values of $K1$ and $K2$ are positive, and $K1 < K2$ is satisfied.

When determining that the nipping pressure is the first nipping pressure, the controller **500** determines the duty cycle on the basis of a third table (an example of the fourth table) illustrated in FIG. 9A and the manipulated variable U . A first duty upper limit, which is the upper limit for the duty cycle in the third table, is 100%.

When determining that the nipping pressure is the second nipping pressure, the controller **500** determines the duty cycle on the basis of a fourth table (an example of the third table) illustrated in FIG. 9B and the manipulated variable U . A second duty upper limit, which is the upper limit for the duty cycle in the fourth table, is 57%. Each of the third table in FIG. 9A and the fourth table in FIG. 9B is a table correlating the manipulated variable U with the duty cycle.

11

In this modification, both the third table and the fourth table are stored in the memory 600 instead of the first table and the second table.

The controller 500 according to this modification is configured to execute processes illustrated in the flowchart of FIG. 8. Since only a part of the flowchart illustrated in FIG. 8 differs from the flowchart of FIG. 6, processes which are the same as those in the flowchart of FIG. 6 are designated with the same step numbers to omit the duplicating description.

As illustrated in the flowchart of FIG. 8, when determining in S2 that the nipping pressure is the first nipping pressure (S2: YES), in S21 the controller 500 selects the third table illustrated in FIG. 9A. After the process of S21, in S22 the controller 500 sets the coefficient K_d of the derivative term to $-K1$. The process in S21 is an example of the selecting the fourth table.

When determining in S2 that the nipping pressure is not the first nipping pressure (S2: NO), in S23 the controller 500 selects the fourth table illustrated in FIG. 9B. After the process of S23, in S24 the controller 500 sets the coefficient K_d of the derivative term to $-K2$. That is, when the nipping pressure is the second nipping pressure, the controller 500 sets the absolute value of the coefficient K_d of the derivative term to a value greater than that when the nipping pressure is the first nipping pressure. The process in S23 is an example of the selecting the third table.

After the process of S22 or S24, the controller 500 executes the processes of S5 and S6. Subsequently, in S25 the controller 500 calculates the manipulated variable U according to expression (1). The process in S25 is an example of the calculating. After the process of S25, in S26 the controller 500 sets the duty cycle on the basis of the third or fourth table selected in the process of S21 or S23 and the calculated manipulated variable U, and controls power supply to the heater 10 using the set duty cycle. Subsequently, the controller 500 executes the processes of S8 and S9, and then ends the routine of FIG. 8.

Also in this modification, the output of the heater 10 is restricted to a value equal to or less than the second output upper limit when the nipping pressure is low, thereby suppressing excessive rise in the temperature of the heater 10 which is caused by supplying power to the heater 10 when the nipping pressure is low.

Although the pressure roller 3 serves an example of the rotary body in the embodiment described above, the present disclosure need not be limited to this configuration. When the components for applying pressure includes an endless pressure belt and a pad that nips the pressure belt in cooperation with the heating unit, the pressure belt may be employed as the rotary body.

The nipping pressure changing mechanism may have a configuration different from that in the above embodiment. For example, the nipping pressure changing mechanism may be configured to change the nipping pressure among three or more stages. Further, the nipping pressure changing mechanism may include a link mechanism that causes the cams 80 to be pivotally moved between the first position and the second position in conjunction with opening and closing movement of the rear cover 123 that opens and closes the second opening H2. In this case, the cams 80 are caused to be pivotally moved to the first position through the link mechanism when the rear cover 123 is moved to be closed, while the cams 80 are caused to be pivotally moved to the second position through the link mechanism when the rear cover 123 is moved to be opened.

12

In the above embodiment, the cover sensor SE1 serves as a sensor configured to detect information for determining whether the nipping pressure is the first nipping pressure or the second nipping pressure. However, other types of sensors are available. For example, a sensor configured to detect a position of the heating unit 2, or a sensor configured to detect attachment and detachment of the process cartridge 150 relative to the main casing 120 may be employed. In a case where the sensor configured to detect attachment and detachment of the process cartridge 150 relative to the main casing 120 is employed, the nipping pressure changing mechanism may cause the cam 80 to be pivotally moved between the first position and the second position in conjunction with the attachment and detachment of the process cartridge 150 relative to the main casing 120.

Although the present disclosure is applied to the laser printer 100 in the above embodiment, the present disclosure may be applied to other types of image forming apparatuses such as a copying machine or a multifunction peripheral.

The parts and components described in the above embodiment and modifications may be combined where appropriate.

What is claimed is:

1. An image forming apparatus comprising:
a heater comprising:
a substrate; and
one or more heating elements;
an endless belt circularly movable around the heater;
a rotary body configured to nip, in cooperation with the heater, the belt therebetween to form a nipping region;
a nipping pressure changing mechanism configured to change a nipping pressure at the nipping region between:
a first nipping pressure; and
a second nipping pressure that is higher than the first nipping pressure; and
a controller configured to perform a control process to control output of the heater, the control process comprising:
determining whether the nipping pressure is the first nipping pressure or the second nipping pressure; and
controlling, when determining that the nipping pressure is the first nipping pressure, the output of the heater within a range that does not exceed a first output upper limit that is an upper limit for the output of the heater when the nipping pressure is the first nipping pressure, the first output upper limit being smaller than a second output upper limit that is an upper limit for the output of the heater when the nipping pressure is the second nipping pressure.

2. The image forming apparatus according to claim 1, further comprising a temperature sensor configured to detect a temperature of the heater,
wherein, in the control process, the output of the heater is set to a greater value as a deviation between a detection temperature and a target temperature is greater, the detection temperature being the temperature of the heater detected by the temperature sensor.

3. The image forming apparatus according to claim 2, wherein, in the control process, the output of the heater is controlled by controlling a duty cycle of power supply to the heater,
the image forming apparatus further comprising a memory storing therein a plurality of tables that correlates the deviation with the duty cycle, the tables comprising:

13

a first table in which an upper limit for the duty cycle is a first duty upper limit; and

a second table in which the upper limit for the duty cycle is a second duty upper limit that is greater than the first duty upper limit,

wherein the first duty upper limit corresponds to the first output upper limit, and the second duty upper limit corresponds to the second output upper limit, and

wherein the control process further comprises:

selecting, when determining that the nipping pressure is the first nipping pressure, the first table to determine the duty cycle on the basis of the deviation; and

selecting, when determining that the nipping pressure is the second nipping pressure, the second table to determine the duty cycle on the basis of the deviation.

4. The image forming apparatus according to claim 3, wherein the second duty upper limit is 100%.

5. The image forming apparatus according to claim 1, wherein, in the controlling, the output of the heater is controlled by controlling a duty cycle of power supply to the heater within a range that does not exceed a first duty upper limit that is an upper limit for the duty cycle when the nipping pressure is the first nipping pressure, the first duty upper limit being smaller than a second duty upper limit that is an upper limit for the duty cycle when the nipping pressure is the second nipping pressure, and

wherein the first duty upper limit corresponds to the first output upper limit, and the second duty upper limit corresponds to the second output upper limit.

6. The image forming apparatus according to claim 1, further comprising a temperature sensor configured to detect a temperature of the heater,

wherein the control process further comprises:

calculating a manipulated variable using a sum of:

a proportional term proportional to a deviation between a detection temperature and a target temperature, the detection temperature being the temperature of the heater detected by the temperature sensor; and

a derivative term proportional to a derivative value of the deviation, the derivative term having a coefficient,

wherein, in the control process, the output of the heater is controlled by controlling a duty cycle of power supply to the heater, the duty cycle of power supply to the heater being set to a greater value as an absolute value of the calculated manipulated variable is greater, and

wherein, in the controlling, the coefficient of the derivative term is set to such a value that the absolute value of the calculated manipulated variable is smaller than when the nipping pressure is the second nipping pressure.

7. The image forming apparatus according to claim 6, further comprising a memory storing therein a plurality of tables that correlates the manipulated variable with the duty cycle, the tables comprising:

a third table in which an upper limit for the duty cycle is a first duty upper limit; and

a fourth table in which the upper limit for the duty cycle is a second duty upper limit that is greater than the first duty upper limit,

14

wherein the control process further comprises:

selecting, when determining that the nipping pressure is the first nipping pressure, the third table to determine the duty cycle on the basis of the absolute value of the manipulated variable; and

selecting, when determining that the nipping pressure is the second nipping pressure, the fourth table to determine the duty cycle on the basis of the absolute value of the manipulated variable.

8. The image forming apparatus according to claim 7, wherein the second duty upper limit is 100%.

9. The image forming apparatus according to claim 1, wherein the determining is performed in response to receiving a printing instruction.

10. The image forming apparatus according to claim 1, wherein the one or more heating elements comprise a plurality of heating elements provided on the substrate and arranged in a conveying direction of a sheet, the heating elements comprising:

a first heating element positioned most upstream among the heating elements in the conveying direction, the first heating element having a most upstream end in the conveying direction; and

a second heating element positioned most downstream among the heating elements in the conveying direction, the second heating element having a most downstream end in the conveying direction, and

wherein, when the nipping pressure is the first nipping pressure, the nipping region has a length in the conveying direction that is shorter than a distance in the conveying direction between the most upstream end and the most downstream end.

11. The image forming apparatus according to claim 10, wherein, when the nipping pressure is the second nipping pressure, the length in the conveying direction of the nipping region is longer than the distance in the conveying direction between the most upstream end and the most downstream end.

12. The image forming apparatus according to claim 1, further comprising a sensor configured to detect information for the controller to perform the determining.

13. The image forming apparatus according to claim 12, further comprising:

a main casing having an opening; and

a cover configured to open and close the opening, wherein the sensor is configured to detect whether the cover closes the opening.

14. The image forming apparatus according to claim 13, wherein the controller is configured to cause the nipping pressure changing mechanism to make the nipping pressure to the second nipping pressure when determining that the cover closes the opening on the basis of the information from the sensor, and to cause the nipping pressure changing mechanism to make the nipping pressure to the first nipping pressure when determining that the cover does not close the opening on the basis of the information from the sensor.

15. An image forming apparatus comprising:

a heater comprising:

a substrate; and

a plurality of heating elements provided on the substrate and arranged in a conveying direction of a sheet, the heating elements comprising:

a first heating element positioned most upstream among the heating elements in the conveying direction, the first heating element having a most upstream end in the conveying direction; and

15**16**

a second heating element positioned most downstream among the heating elements in the conveying direction, the second heating element having a most downstream end in the conveying direction; 5
an endless belt circularly movable around the heater; 5
a rotary body configured to nip, in cooperation with the heater, the belt therebetween to form a nipping region; and
a controller, 10
wherein the nipping region has a length in the conveying direction that can be changed between:
a first length that is shorter than a distance in the conveying direction between the most upstream end and the most downstream end; and
a second length that is longer than the distance in the 15 conveying direction between the most upstream end and the most downstream end, and
wherein the controller is configured to perform a control process to control output of the heater, the control process comprising: 20
controlling, when the length in the conveying direction of the nipping region is the first length, the output of the heater within a range that does not exceed a first output upper limit that is an upper limit for the output of the heater when the length in the conveying 25 direction of the nipping region is the first length, the first output upper limit being smaller than a second output upper limit that is an upper limit for the output of the heater when the length in the conveying direction of the nipping region is the second length. 30
